ELECTRIC FENCE IMPULSE CONTROL SYSTEM

Lyman E. Greenlee, Anderson, Ind.

Application April 6, 1944, Serial No. 529,731

8 Claims. (Cl. 256—10)

1

This invention relates to an improved system of electric fence impulse control to confine live-stock or other animals.

The invention relates primarily to means of construction of the controlling apparatus and stock enclosure in such a way that the mechanism does not operate unless an animal actually touches some part of the enclosure.

A further object of the invention is to provide a mechanism that will use much less current than other systems now in use.

Another primary object of the invention is to provide a means for greatly reducing the mechanical wear on circuit breakers and contact points.

That my invention may be more fully understood, reference is made to the accompanying drawings which form a part of this description, in which:

Figure 1 shows a wiring diagram of the invention.

Figure 2 shows a modified circuit for use with transposed fence wires.

Figure 3 shows essentially the same circuit as shown in Figure 2, connected for use with a single fence wire, and with input sensitivity control.

The interrupter I shown in Figures 1 to 3 consists of one movable and one fixed contact, normally closed, and so designed and mounted that the magnetic attraction from the iron core of the fence transformer T will cause these contacts to open and thus interrupt the circuit. In its simplest form, the interrupter I and transformer T could be a spark coil of the automotive ignition type. For use with electric fencing, a rotor mechanism or other type of mechanical delay action is usually provided to slow down the frequency of operation of the interrupter to one or two contacts per second. The combination of interrupter I, condenser C1 and fence transformer T may be considered as a unit which may be chosen from any one of several such devices now on the market.

Details of the actual mechanical construction of such a device have been purposely omitted from my explanation because my invention does not relate to the construction of such devices. When operating at 1 second intervals (electric fence safety regulations now call for an "on" period of $\frac{1}{6}$ second or less and an "off" period of at least $\frac{3}{4}$ second) this contact mechanism will operate 3600 times in one hour, and will operate 86,400 times in 24 hours. The system of electric fencing which I have invented operates on an average of 15 or 20 times during a 24 hour

2

period. The saving in wear and current is quite obvious. Another very important point to consider is the fact that with my system the shock impulse can be made much stronger than with the method described above. This is true because with a mechanism making 86,400 impulses a day, each separate impulse must be very weak or the battery would be exhausted very quickly.

Manufacturers of such devices, in order to secure reasonably satisfactory battery life, have constructed mechanisms in such a way that the shock impulses are barely strong enough to control the animals when batteries are new, fences are well insulated, and the mechanism is in perfect working order. With a partly run-down battery or partly grounded fence, such a mechanism becomes worthless for the purpose for which it was intended, and this is one of the primary reasons why such mechanisms have not come into more general use, although some of them were patented almost 60 years ago.

In Fig. 1, the fence wires F1 and F2 are supported on insulators 5 attached to posts M and are spaced closely together. An animal crowding into the fence will form a connection between F1 and F2 by touching these two wires. A drop in the electrical resistance between F1 and F2 is sufficient to actuate the sensitive vacuum tube or electronic relay V. Relay tube V is a triode or three-element tube containing a grid 10, plate 11, and cathode 9 and filled with a conductive gas. Tube V is so constructed that the application of a small voltage to the grid 10 will cause a current to flow between plate 11 and cathode 9 and this current is used to operate relay R2. Tube V remains non-conductive when no voltage is applied to the grid 10, which is connected to F1 through potentiometer 16. Fence wire F2 is connected to battery B in such a way as to apply the voltage from battery B between cathode 9 and grid 10 whenever a connection is made between F1 and F2. Potentiometer 16 is connected between fence F1 and cathode 9 and serves the purpose of limiting and controlling the sensitivity of relay-tube V. Whenever the tube V becomes conductive, current flows from battery B through relay armature 13 to upper fixed contact 12, to cathode 9, to plate 11, through relay coil 15, and back to battery B. Armature 13 is then attracted to fixed contact 14 and the circuit is completed between battery B and the primary P of fence transformer T through interrupter I. A shock impulse then appears between F2 and ground. The charge stored in condenser C2 serves to delay the opening of relay armature 13 until the

interrupter I has had an opportunity to function. Relay R2 serves the double purpose of connecting the primary of the fence transformer to the battery and simultaneously opening the circuit to the cathode of the relay-tube, so that the tube will become non-conductive and the entire system will be ready for another cycle of operation upon the opening of the relay armature. However, the fence wire F2 receives intermittent impulses through the action of interrupter I as long as F1 and F2 are contacted, and the frequency of these impulses will depend on the timing of the interrupter I.

Figure 2 shows a modified circuit with transposed fence wires. The cathode 9 of tube V is connected to interrupter I along with the primary P of the fence transformer, and upper relay contact 12 can thus be omitted. When switch 20 is closed and a single wire fence connected to F1 the impulse control mechanism is shorted. This is also true for Fig. 3. In Fig. 2, a contact between F1 and F2 or between F2 and ground is sufficient to actuate relay tube V because F1 is connected to the ground through the secondary S of the fence transformer, which is also connected to the opposite pole of battery B so that the E. M. F. of B is across the plate 11 and cathode 9 of V. The contact points of relay R1 designated as 13 and 14 are normally open; when closed, they complete the circuit through the battery B to the primary of the transformer P and interrupter I, thus producing a series of shock-impulses across the secondary S of the transformer, or between F1 and ground as interrupter I functions. Operation of the device is as follows: An animal crowds against the fence, and thus makes contact either between F2 and ground through body resistance, or between F1 and F2 and ground; however, a contact with F1 is also a contact with ground through the secondary of the transformer S which has sufficiently low resistance to pass enough current from the battery B to actuate the tube V. Current passes from battery B to ground through the transformer secondary S and back through the animal to F2 or directly to F2 from F1 in case the animal forces the wires to contact. Current then passes through potentiometer 16 to tube cathode 9 and back to battery B through the normally closed contacts of interrupter I. A portion of this current is supplied to grid 10 of tube V causing the tube to become conductive and to allow a current to flow from cathode 9 to plate 10 through coil 15 of relay R1 to battery B. Relay contacts 13 and 14 are caused to close and this action completes the circuit to the primary P of the transformer through interrupter I, however, as soon as the interrupter I points open, the circuit to the control tube cathode is broken, the tube is extinguished, the armature of relay R1 opens, and a shock impulse is transferred to the fence. Note that condensers C2 and C3 may be omitted without seriously affecting the operation of the device when used as shown in Fig. 2. However, these condensers will be needed to bypass shock-impulses when the device is used with one wire as shown in Fig. 3. Fig. 3 shows the same mechanism of Fig. 2, connected to function with a single wire and ground return. When used in this way, it is desirable to add a choke coil Ch in series with the grid 10 and potentiometer 16 to keep shock-impulses from "back-firing" through tube V. Fig. 3 also shows the use of expansion and contraction of hygroscopic material 19 to actuate the arm of potentiometer

16 and afford automatic control of input sensitivity. Hygroscopic material 19 is fastened at one end to support 17 and to the other end to the arm of potentiometer 16, while spring 18 attached to support 17 serves to maintain tension on the potentiometer arm to enable its control by 19, and this control is preferably effected by means of a system of gears and/or levers used to multiply the very minute motion of 19. I have omitted mechanical details of such a system of gears or levers because the construction of such devices is not beyond average mechanical skill. Operation of Fig. 3 is as follows: An animal touching fence wire F2 completes the circuit from the battery B through the secondary of the transformer S to ground, and through the animal from ground to F2, and through F2 to potentiometer 16, to cathode 9 of tube V and back to battery B through the normally closed points of interrupter I. A portion of the voltage across potentiometer 16 is transferred through the choke coil Ch, which has a low D. C. resistance, to the grid 10 and this voltage renders the tube V conductive and allows a current to flow from cathode 9 to plate 11 through coil 15 of relay R1 to battery B. Relay contacts 13 and 14 are closed by magnetic attraction and condenser C2 is charged. Condenser C2 has sufficient capacity to store up enough current to hold the relay points closed until the interrupter I has had an opportunity to open and close several times and send several shock impulses back through the fence. Since F1 has been disconnected temporarily as shown in Fig. 7, the shock impulse must pass from the secondary of the transformer S back through relay contacts 13 and 14, through the primary P to the cathode of tube V and through C3 to wire F2, and from F2 through the animal to ground. If wire F1 is used (as shown in Fig. 2) the shock impulses pass directly from F1 through the animal to ground, and C3 is not needed. Otherwise, the omission of C3 would result in a weak shock output, owing to the resistance of potentiometer 16 which must be rather high to secure adequate sensitivity. In Figs. 2 and 3 I have shown a mechanism that may be used in three different ways: (a) As a simple impulse generator with the fence connected to F1 and switch 20 closed. (b) With transposed fence wires as shown in Fig. 2. (c) With a single fence wire F2 and ground return to provide electronic impulse control as shown in Fig. 3. A wide variation of battery voltage is permissible with proper design of component parts. It is assumed that a battery with a voltage of from 6 to 100 will ordinarily be used, and it is believed that most satisfactory operation will be secured if an ordinary 45-volt radio "B" battery is used as the source of current.

(A battery is shown as the source of current in Figures 1 to 3, inclusive, but any other source of electric energy could be used by employing suitable transformers and rectifiers to provide an output equivalent to that of the battery.)

In making an analysis of Figures 1, 2 and 3, it is desirable to point out that (as shown in Figure 65) 2) bypass condensers C2 and C3 may be omitted without rendering the device inoperative. These condensers would normally be included to secure greater and more uniform shock output, but their removal does not prevent the instrument from working. The choke coil Ch shown in Figure 3 may likewise be omitted since its primary function is to protect tube V from surge voltage discharges. In Figure 3 it is obvious that the potentiometer 16 may be manually adjusted as shown 70 in Figures 1 and 2 rather than through the ex-

pansion of some material which is actuated by moisture in the air. While the above mentioned parts are very desirable to make a smooth working instrument, they are not to be regarded as essential.

I have shown the evolution of an improved method whereby a fence controller can be made to operate only when an animal touches the fence enclosure, and this constitutes the basis of my invention. I believe my method of accomplishing this to be new, and that I am the original inventor of this new system of electric fencing.

I have avoided showing any particular details of mechanical construction of controller mechanisms as it is obvious that an infinite number of mechanical variations is possible without alteration of the fundamental principles of operation as outlined above in my patent application.

Having thus described my invention, what I claim as new is:

1. In combination with a fence structure insulated from the ground, a fence transformer with a primary winding in series with a battery and the normally closed contact points of an interrupter, an electromagnetic relay with normally open contacts in series with the plate of a three-element cold-cathode electron control tube connected to cause the operation of the said electromagnetic relay whenever there is a drop in the resistance between the grid and cathode of the said control tube, a condenser in parallel with the interrupter points, a condenser in parallel with the relay coil, a potentiometer connected between the grid and cathode of the said control tube and the fence circuit, a condenser in parallel with the said potentiometer, an iron core choke coil in series with the said potentiometer contact arm and the grid of the said control tube, and hygroscopic material attached to move the contact arm of the said potentiometer with changes in relative atmospheric humidity.

2. In combination with a fence structure consisting of fence wires insulated from the ground, a fence transformer with a primary coil in series with a battery, the normally closed contacts of an interrupter, and the normally open contacts of an electromagnetic relay; a three-element electron control tube connected to cause the operation of the electromagnetic relay with a drop in resistance between the grid and cathode of the said tube, a condenser in parallel with the interrupter contact points, a potentiometer connected between the grid and cathode of the said tube and the fence circuit, a condenser in parallel with the said potentiometer, an iron core choke coil in series with the said potentiometer contact arm and the grid of the said control tube, a condenser in parallel with the coil of the said electromagnetic relay, and hygroscopic material attached to move contact arm of said potentiometer with changes in relative atmospheric humidity.

3. In combination with a fence structure consisting of fence wires insulated from the ground, a fence transformer with a primary winding in series with the normally closed contact points of an interrupter, a battery, and the normally open contacts of an electromagnetic relay, and with the secondary of the said fence transformer connected to the battery and between a fence wire and ground; a three-element cold cathode electron control tube connected to the fence to actuate the said electromagnetic relay with a drop in resistance between the said fence and ground; a condenser in parallel with the interrupter con-

tact points, a potentiometer connected between the grid and cathode of the said control tube and the fence circuit, a condenser in parallel with the resistance winding of said potentiometer, an iron core choke coil in series with the said potentiometer arm and the grid of the said control tube, a condenser in parallel with the coil of the said electromagnetic relay, and hygroscopic material attached to move the contact arm of the said

5 potentiometer with changes in the length of the 10 said hygroscopic material due to the expansion and contraction with changes in relative atmospheric humidity.

4. In combination with a fence insulated from 15 the ground, a battery in series with the primary of a transformer, an interrupter, and the normally open contacts of a separate relay; with the said relay coil connected in series with the plate circuit of a three element cold-cathode control tube; and with the grid of said tube connected through 20 a variable potentiometer to the fence, and the cathode connected to the battery through the interrupter.

5. In combination with an insulated fence 25 structure, a battery in series with the primary and secondary of a transformer, an interrupter having a condenser in parallel with its normally closed contact points, and the open contacts of 30 a relay switch; with the coil of the said relay switch connected in series with the plate circuit of a three element cold-cathode control tube; with the grid of the said tube connected through a variable potentiometer to the insulated fence structure, and the cathode connected to 35 the battery through the interrupter contact points.

6. An electrical circuit consisting of an insulated barrier, a source of direct current insulated from the ground and connected to the said barrier; a transformer, a normally closed interrupter, and normally open relay contact points connected in series and to the current source; and with the coil of the said relay in series with the plate circuit of a three element cold-cathode control 45 tube, with the cathode of the said tube connected to the primary circuit of the fence transformer, and the grid connected to the barrier through a variable potentiometer.

7. In combination with separate fence structures insulated from the ground and from each other, a battery in series with the primary of a transformer, a normally closed interrupter, and the normally open contacts of a single pole double throw relay switch mechanism having its normally closed contact connected to the cathode of a three element vacuum tube, with the coil of the said relay in series with the plate circuit of the said tube, and with the grid of the said tube connected through a potentiometer between the cathode and one of the insulated fence structures; with the other insulated fence structure connected to the battery.

8. In combination with separately insulated and ungrounded fence structures, a source of current insulated from the ground and in series with the primary of a transformer having an attached interrupter by-passed by a condenser, and also in series with the two normally open contacts of a relay switch; with the coil of the said relay switch in series with the plate circuit of a three element cold-cathode vacuum tube; with the cathode of the said tube connected to the transformer primary; the grid of the said tube connected to a fence structure through a potentiometer between one fence structure and

tube cathode; and with the other fence structure connected to the secondary of the transformer and to the source of current.
